(57) **CLAIM**

The ornamental design for a partition, as shown and described.

DESCRIPTION

FIG. 1 is a perspective view of a partition showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIGS. 8-9 are perspective views showing the partition installed inside a drawer.

The broken line portions of the partition in FIGS. 1-3 and 6-9 represent unclaimed portions of the claimed design and form no part thereof. The broken lines of the drawer in FIGS. 8-9 illustrate unclaimed environment and forms no part of the claimed design.

1 Claim, 7 Drawing Sheets
